(57) **CLAIM**

The ornamental design for a tray for a stationary bicycle, as shown and described.

DESCRIPTION

FIG. 1 is an isometric view of a tray for a stationary bicycle, showing my new design as mounted upon a stationary bicycle;

FIG. 2 is a top view of a tray for a stationary bicycle, showing my new design;

FIG. 3 is a front end view thereof;

FIG. 4 is a left side view thereof;

FIG. 5 is a right side view thereof;

FIG. 6 is a rear end view thereof;

FIG. 7 is a bottom view thereof; and,

FIG. 8 is an isometric view thereof.

The broken lines in FIG. 1 are included for the purpose of illustrating the invention in use, and form no part of the claimed design.

1 Claim, 5 Drawing Sheets
